UNITED STATES PATENT OFFICE

FRITZ B. ERNST, OF CHICAGO, ILLINOIS, ASSIGNOR TO AMERICAN STEEL FOUNDRIES,
OF CHICAGO, ILLINOIS, A CORPORATION OF NEW JERSEY

SIDE FRAME FOR TRUCKS

Application filed October 11, 1928. Serial No. 311,802.

This invention relates to truck side frames.

As is well appreciated, while a cast steel side frame is simple in construction, the 5 stress conditions set up therein are rather complicated. It is subject to a direct vertical load carrying the weight of the car and its lading, which load is received through the bolster springs. This direct 10 loading is accentuated by the action of the bolster springs.

The side frame also receives a transverse load delivered in the nature of shocks or blows occasioned by the longitudinal shifting 15 of the truck bolster which delivers the shocks or blows to the side frame through the columns of the bolster and of the side frames. The side frame is also subjected to a twisting or torsional load when the car 20 strikes or rounds a curve. This load is especially severe if the spring plank connecting the two side frames is riveted securely thereto.

In cast or integral side frames in which 25 all the various members of the frame are joined rigidly, the various direct loads which produce direct stresses also produce secondary or induced stresses. At some points on the casting, the secondary stresses 30 are greater or more serious than the primary stresses. Some of the portions of the casting are subject to two primary stresses and in addition several secondary stresses. In adding various stresses algebraically, it is 35 found that at several points in the frame all the stresses which localize at these points happen to be plus or tension stresses with no corresponding minus or compression 40 stresses to lower the average.

One object of the invention is to provide a truck side frame in which the stresses are more evenly distributed and balanced in the general type of side frame herein disclosed 45 and whereby such side frame is materially strengthened at critical points without appreciably increasing the weight of the frame.

Another object is to provide an integrally 50 formed truck side frame adapted to meet

the various requirements under severe service conditions.

These and other objects are accomplished by means of the truck side frame disclosed by the accompanying sheet of drawing, in 55 which—

Figure 1 is a fragmentary side elevation of a truck side frame embodying my invention;

Figure 2 is a fragmentary bottom plan 60 view of the same side frame;

Figure 3 is a sectional view taken in the plane of line 3—3 of Figure 1; and

Figure 4 is a sectional view taken in the plane of line 4—4 of Figure 1. 65

The various novel features of the invention will be apparent from the following description and drawing and will be particularly pointed out in the appended claims.

Referring to the figures of the drawing, 70 it will be noted that the side frame disclosed includes a compression member 10 which extends from one end of the frame to the other and terminates in an integrally formed journal box 11. The tension member in- 75 includes a horizontally extending portion 12 between the the columns 13 and an inclined portion 14 extending upwardly and outwardly from the columns to a point of junction with the compression member 10 at 80 the associated journal box 11.

Generally speaking, that portion 12 of the tension member between the columns 13 is box shaped in section, as shown in Figure 3, and that portion of the tension member 85 14 intermediate the columns and the journal boxes is channel shaped in section, as shown in Figure 4, with the web 15 being at the upper side.

The side frame is integrally formed, that 90 is, the tension and compression members and columns 13 are cast in a single piece. In this particular instance, the journal boxes 11 are also cast integrally with the side frame. 95

The various stresses and strains set up in an integrally formed side frame are considered in detail in the Floyd Patent No. 1,364,491, dated January 4, 1921, and it will therefore be unnecessary to describe in de- 100

tail just what the stresses and strains are. It will be sufficient to state that the bending and tension stresses ordinarily would be greatest and excessive at the under side 5 of the tension member portion 12 between the columns 13 and at the upper side of the tension member portions 14 directly outwardly from the columns, and also at the under side of the tension member directly 10 inwardly from the journal boxes 11. In this particular instance, the stresses developed at either side of the columns are of particular interest.

In order to distribute the tension stresses 15 in the tension member in a manner to reduce the bending stresses at the points mentioned, the web 15 of the tension member continues from a point 16 downwardly and inwardly as at 17 and passes diagonally 20 through the associated column 13. It emerges from the inner side thereof and continues to extend downwardly and inwardly to form an angular portion 18 in the lower corners formed by the columns 13 25 and the tension member portion 12. Said web 17 tapers into the upper surface of the spring seat portion 19 of the tension member between the columns 13.

The triangular portion 18 referred to includes not only the web 17 but also vertical flanges 20 which connect the web 17 with the spring seat portion 19 and with the inner walls of the columns 13.

In this way the various parts of the tension member and columns are tied together 35 in a manner to properly distribute the tension stresses in the tension member and to reduce the bending stresses at the points mentioned.

40 By this arrangement the objects of the invention are accomplished.

It is my intention to cover all modifications of the invention falling within the spirit and scope of the following claims.

45 I claim:

1. A truck side frame including tension and compression members and columns all cast in a single piece whereby and wherein bending stresses ordinarily would be greatest and excessive at points on either side of each of the columns, said tension member 50 being channel shaped in section and having its web at the upper side, said web extending through the associated column 55 and continuing into the spring seat portion of the tension member between said columns to distribute the tension stresses in the tension member in a manner to reduce the bending stresses at the points mentioned.
- 60 2. A truck side frame including tension and compression members and columns all cast in a single piece whereby and wherein bending stresses ordinarily would be greatest and excessive at points on either side 65 of each of the columns, said tension mem-

ber being channel shaped in section and having its web at the upper side, said web extending diagonally through the associated column and continuing into the spring seat portion of the tension member between said 70 columns to distribute the tension stresses in the tension member in a manner to reduce the bending stresses at the points mentioned.

3. A truck side frame including tension 75 and compression members and columns all cast in a single piece whereby and wherein bending stresses ordinarily would be greatest and excessive at points on either side of each of the columns, said tension member 80 being channel shaped in section and having its web at the upper side, said web extending diagonally through the associated column and tapering downwardly into the spring seat portion of the tension member 85 between said columns to distribute the tension stresses in the tension member in a manner to reduce the bending stresses at the points mentioned.

4. A truck side frame including tension 90 and compression members and columns spacing intermediate portions of said members, one of said members having inclined portions of substantial quadrilateral shape comprising a web and spaced flanges, said 95 web intersecting said columns and merging into a portion of one of said members between said columns, and spring seats disposed on one side of said web.

5. A truck side frame including tension 100 and compression members and columns spacing intermediate portions of said members, one of said members having inclined portions of substantial quadrilateral shape comprising a web and a flange portion, one 105 of said last named portions intersecting said columns and merging into the portions of said members between said columns, and spring seats disposed on one side of said web.

6. A truck side frame including tension and compression members and columns spacing intermediate portions of said members, one of said members having inclined portions of substantial box shape, a portion 115 of said member intersecting said columns and merging into the portion of one of said members between said columns, and spring seats disposed on one side of said web.

7. A truck side frame including tension 120 and compression members and columns spacing intermediate portions of said members, journal boxes formed integral with said tension and compression members, one of said members having inclined portions 125 of substantial channel shape comprising a web portion and a flange portion, one of said last named portions being in substantial alignment with a corner of said journal box and intersecting said columns above the 130

- bases thereof and merging into a portion of one of said members between said columns.
8. A truck side frame including tension and compression members and columns spacing intermediate portions of said members, one of said members having inclined portions of substantial quadrilateral shape comprising a web and spaced flanges, said web intersecting said columns above the bases thereof and continuing in a substantially unbroken contour to merge into a portion of one of said members between the columns.
- 15 9. A truck side frame including tension and compression members and columns spacing intermediate portions of said members, one of said members having inclined portions of substantial quadrilateral shape comprising a web and a flange portion, one of said last named portions intersecting said columns above the bases thereof and continuing in a substantially unbroken contour to merge into a portion of one of said members between the columns.
- 20 10. A truck side frame including tension and compression members and columns spacing intermediate portions of said members, said tension member having inclined portions of substantial box shape, a portion of said tension member intersecting said columns above the bases thereof and continuing in a substantially unbroken contour to merge into a portion of one of said members between the columns.
- 25 11. A truck side frame including tension and compression members and columns spacing intermediate portions of said members, said tension member having inclined portions of substantial box shape, a portion of said tension member intersecting said columns above the bases thereof and continuing in a substantially unbroken contour to merge into a portion of the tension member between the columns.
- 30 12. In a side frame, the combination of tension and compression members merging adjacent the ends thereof and provided with journal boxes at said merged ends, spaced integral column guides connecting said tension and compression members, one of said members having a web merging into said journal box adjacent the inner corner thereof, said web intersecting one of said column guides above the bases thereof and merging into one of said members intermediate said column guides, and gusset members merging into said journal box adjacent said corner thereof.
- 35 13. A truck side frame including tension and compression members and columns spacing intermediate portions of said members, one of said members having inclined portions of substantial quadrilateral shape comprising a web and spaced flanges, said web intersecting said columns above the bases thereof and continuing diagonally to merge into a portion of one of said members between said columns.
- 40 14. In a side frame, the combination of tension and compression members merging adjacent the ends thereof and provided with journal boxes at said merged ends, spaced integral column guides connecting said tension and compression members, one of said members having a web merging into said journal box adjacent the inner corner thereof, said web intersecting one of said column guides above the bases thereof and merging into one of said members intermediate said column guides, and gusset members merging into said journal box adjacent a corner thereof.
- 45 15. In a side frame, the combination of tension and compression members merging adjacent the ends thereof and provided with journal boxes at said merged ends, spaced integral column guides connecting said tension and compression members, one of said members having a web merging into said journal box adjacent the inner corner thereof, said web intersecting one of said column guides above the bases thereof and merging into one of said members intermediate said column guides, and gusset members merging into said journal box adjacent said corner thereof.
- 50 16. In a side frame, the combination of tension and compression members merging adjacent the ends thereof and provided with journal boxes at said merged ends, spaced integral column guides connecting said tension and compression members, one of said members having a web merging into said journal box adjacent the inner corner thereof, said web intersecting one of said column guides above the bases thereof and merging into one of said members intermediate said column guides, and gusset members merging into said journal box adjacent a corner thereof and being substantially aligned with said web.
- 55 17. In a side frame, the combination of tension and compression members merging adjacent the ends thereof and provided with journal boxes at said merged ends, spaced integral column guides connecting said tension and compression members, one of said members having a web merging into said journal box adjacent the inner corner thereof, said web intersecting one of said column guides above the bases thereof and merging into one of said members intermediate said column guides, and gusset members merging into said journal box adjacent a corner thereof and being substantially aligned with said web.
- 60 18. A side frame comprising a member formed with a tension and a compression member having columns therebetween, said tension member including a spring seat member forming a bolster opening with said

columns and compression member, said tension and compression members merging into a portion provided with a journal box, said tension member having a web merging into a corner of said journal box and intersecting one of said columns above the base of said column and extending to and merging into said spring seat member.

19. A side frame comprising a member
10 formed with a tension and a compression
member having columns therebetween, said
tension member including a spring seat
member forming a bolster opening with said
columns and compression member, said ten-
15 sion and compression members merging into
a portion provided with a journal box, one
of said first named members having a web
merging into a corner of said journal box
and intersecting one of said columns above
20 the base of said column and extending to
and merging into said spring seat member.

Signed at Chicago, Illinois, this 4th day
of October, 1928.

FRITZ B. ERNST.
